US00D964346S

(12) **United States Design Patent** (10) **Patent No.:** **US D964,346 S**
(45) **Date of Patent:** **** Sep. 20, 2022**

(54) **DISPLAY**

(71) Applicant: **Elo Touch Solutions, Inc.**, Milpitas, CA (US)

(72) Inventor: **Brian Perry**, San Jose, CA (US)

(73) Assignee: **Elo Touch Solutions, Inc.**, Milpitas, CA (US)

(**) Term: **15 Years**

(21) Appl. No.: **29/708,468**

(22) Filed: **Oct. 7, 2019**

Related U.S. Application Data

(63) Continuation of application No. 29/628,625, filed on Dec. 6, 2017, now Pat. No. Des. 864,194.

(51) **LOC (13) Cl.** **14-02**

(52) **U.S. Cl.**

USPC **D14/336**

(58) **Field of Classification Search**

USPC D14/336, 337, 373, 374, 375, 376, 377, D14/125, 128, 129, 126, 127, 371, 372, D14/341

CPC G06F 1/1601; G06F 1/1605; G06F 1/162

(57) **CLAIM**

The ornamental design for a display, as shown and described.

DESCRIPTION

FIG. 1 is a bottom rear perspective view of a display showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dot-dash broken lines in the figures show environment that forms no part of the claimed design. The evenly spaced dashed broken lines show portions of the display that form no part of the claimed design.

1 Claim, 5 Drawing Sheets
